UNITED STATES PATENT OFFICE

CARL SCHRAMM, OF WEST HARTFORD, CONNECTICUT, ASSIGNOR TO THE SMYTH MANUFACTURING COMPANY, OF HARTFORD, CONNECTICUT, A CORPORATION OF CONNECTICUT

FEED MECHANISM FOR CASING-IN MACHINES

Application filed October 14, 1931. Serial No. 568,680.

This invention relates to mechanism provided for feeding fillers into a machine which is designed to apply cases to the fillers, of the type illustrated in United States Patent No. 1,765,349, June 17, 1930.

The object of this invention is to provide means for such a book binding machine, which will receive the fillers and rapidly feed them into exact position to be properly carried up to the cases without liability of damaging, marring or soiling any of the leaves of the fillers or allowing them to become displaced and so interfere with the continuous operation of the machine, the means being so designed that fillers of different thicknesses, widths and heights and of different weights of paper may be equally well fed into proper position to be accurately raised into the cases.

In the embodiment of the invention illustrated the fillers are opened at the middle by the operative and placed on a separator plate with their free edges extending downward between low guide rails and resting on a supporting bar. The fillers are pushed from this initial position along the separator plate and supporting bar to a second position by a finger which engages the edges of the fillers near their backs. From this second position they are advanced to a third position by a finger which engages the edges and by jaws which grasp the fillers at the joints underneath the backs. From this third position they are carried by jaws onto the saddle from which they are lifted to the cases.

The actuating mechanisms so co-operate that the fingers and jaws swing into position and move in a right line to feed the fillers, and then swing out and return for following fillers synchronously, thus there are four fillers being fed into the machine at the same time.

Fig. 1 of the accompanying drawings is a side elevation of the filler feed mechanism, and so much of the adjacent parts of the casing-in machine as is necessary to an understanding of the relation of the feed to the machine. Fig. 2 is a plan view of the runway along which the fillers are fed. Fig. 3 on larger scale shows a front elevation of the runway and first feed finger engaging a filler.

Fig. 4 is a vertical section of the runway on the plane indicated by the dotted line 4-4 on Fig. 2. Fig. 5 is a vertical section on the plane indicated by the dotted line 5-5 on Fig. 1, showing the first conveyer clamp engaging a filler at the joints under the back. Fig. 6 is a vertical section showing the second clamp engaging a filler. Fig. 7 shows details of the means for oscillating the fingers and clamps into and out of the path of the fillers.

In the illustrations 1 indicates the saddle plates of a casing-in machine. These plates are spaced apart and between them passes up a blade 2 that enters the opened fillers which are fed onto the saddle and carries them up to the cases, as described in the patent above referred to.

The separator plate 3 has its inner end fastened to the saddle plates by a fin 4 that extends upward from a supporting bracket 5 which is secured to the frame bar 6. The front end of the saddle plate is fastened to a bracket 7 that is secured to the frame bar 8. The front edge of the saddle plate is beveled and inclined to facilitate the placing by the operative of the opened fillers in initial position on the separator plate, a filler in initial position being indicated by the dotted lines 9 on Fig. 1. The lower part of the central section of the separator plate is cut away so that there will be but slight frictional resistance or rubbing of the leaves by the surface of the separator plate as the fillers are fed along it.

When the fillers are thrust over the separator plate their lower or opened edges rest upon the supporting bar 10. The upper surface of the supporting bar is usually convex and it extends from the front of the machine nearly to the inner end of the separator plate which is above it.

The supporting bar is fastened in a channel shaped member 11, the front end of which member is fixed to a post 12 while the rear end is fixed to a post 13. These posts are capable of being adjusted vertically by screws 14 for the purpose of raising or lowering the channel member and locating the supporting bar according to the width of the fillers which

are to be fed, as specified in the patent referred to.

On the upper edges of the channel member are transversely movable slide plates 15, to the inner edges of which the guide rails 16 are fastened. These guide rails extend in the channel member parallel with the supporting bar and retain the lower edges of the fillers from separating as the fillers are fed along the supporting bar. The slide plates may be moved in and out in order to adjust the space between the guide rails according to the thickness of the fillers, by rocker arms 17 fastened to shafts 18 which are capable of being given rotary movements by rocker arms 19 that engage nuts 20 on screws 21.

Adjustably mounted on the slide plates at the front are guide blocks 22 adapted to direct the lower edges of the fillers when they are passed by the operative into the machine. Filler guiding walls 23 may also be attached to the slide plates adjacent to the initial filler position, which guiding walls are adapted to be removed when the fillers are of narrow width.

Pivoted on top of one of the slide plates is a gauge 24. A spring 25 yieldingly retains the gauge with its inner end extending into the path of the fillers. The operative pushes the fillers into the machine past the gauge and then draws them back against it so that they will be located over the separator plate and on the supporting bar in correct initial position.

A gauge 26 is pivotally mounted on the slide plate and retained by a spring 27 so that its inner end that extends into the path of the fillers will yield when a filler is fed past it but will prevent the filler from being accidentally drawn backward by the return movement of the means which feeds it from second position to third position on the supporting bar and over the separator plate.

The supporting bar and the slide plates with the guide rails and the gauge stops being all carried by the channel member are raised and lowered together to adjust them according to the size of the fillers to be fed.

As in the machine of the patent referred to the present feed has two shafts 28 and 29 that extend parallel with each other and with the supporting bar and separator plate, the shaft 28 being capable of rotary movements and the shaft 29 being held against such movements. Fastened to the shaft 28 is a toothed segment 30 engaged with which is a toothed segment 31 that is oscillated at the required times by suitable mechanism (Fig. 7).

The edges of the fillers placed by the operative over the separator plate are engaged and pushed from initial to second position (indicated by dotted lines 32 on Fig. 1) by a finger 33 pivoted on a block 34 which is splined upon the shaft 28 so that while capa-

ble of being moved along the shaft it will be rotated thereby. From second position the fillers are pushed to third position (indicated by dotted lines 35, Fig. 1) by a finger 36 pivoted on a block 37 which is splined upon the shaft 28. Each of these fingers 33 and 36, as seen in Fig. 3, comprises a member 38 designed to engage the edges of the fillers near the backs, and a member 39 adapted to engage the edges of the fillers further away from the backs and they are retained in normal position by springs 40. The fingers are connected by a rod 41 and the blocks are connected to a shaft 42 so that they will move together along the shaft 28 and will also swing in and out together as this shaft is turned.

Movable along the shafts 28 and 29 is a frame 43. This frame carries a pair of rotary shafts 44 to which jaws 45 are clamped, Fig. 5. The shafts 44 are connected by intermeshing toothed segments 46, one of which has a rocker arm 47 that is connected by a link 48 with a rocker arm 49 that is splined on the shaft 28, Fig. 7, so that the rotary movements of the shaft 28 will cause the jaws 45 to open and close. These jaws are so located and they are so reciprocated and oscillated with the pusher fingers that they grip the fillers at the joints underneath the backs as shown in Fig. 5, and carry the fillers assisted by the pusher finger 36 from second position to third position.

Also mounted on the shafts 44 carried by the frame 43 are clamping jaws 50, Fig. 6. These jaws are opened and closed by the turning of the shafts 44, and they move back and forth with the frame 43 in such manner as to engage the fillers at the joints and carry them from third position onto the saddle plates 1. Movable with the frame is a finger 51 that is yieldingly mounted in an arm 52 which is fastened to a bushing 53 keyed to the shaft 28, Fig. 6. This last mentioned finger is so located and operated that it is back of the edges of the fillers when they are on the saddle and prevents them from being drawn backward should they tend to adhere to the clamp jaws.

The fingers swing in back of and the clamps close on the respective fillers and move forward together to carry the fillers from station to station, and then the fingers swing out and the clamps open together and return for the following fillers, the mechanisms for causing the synchronous reciprocation and oscillation of these members being similar to those fully set forth in the patent before referred to.

The feed mechanism herein described is of particular advantage when fillers with uncut edges, or with rough untrimmed edges, or with gilded or stained edges are being fed. As the separator plate extends from the front of the machine to the saddle, the uncut, or

rough, or treated edges pass smoothly onto the saddle, there being no members which can catch and tear or otherwise mar or injure the edges. The separator plate has a minimum area and the guide rails are low, so that there is but slight frictional resistance to the feed of the fillers, and which feature also eliminates the possibility of the collection of glue on the plates and rails, and the smudging of the printed matter on the inner pages and soiling of the outer pages of the fillers. The fingers and clamp jaws so advance the fillers that they do not tip up when fed along the supporting bar and over the separator plate and thus become torn or jammed so as to interrupt the normal continuous rapid operation of the machine.

The invention claimed is:

1. Mechanism for feeding fillers to the saddle of a casing-in machine, comprising a supporting bar extending from the front of the machine and terminating adjacent to the saddle, a separator plate extending from the front of the machine and terminating at the saddle, guide rails parallel to and extending each side of the supporting bar, and fingers for pushing and clamping jaws for conveying the fillers along the supporting bar and over the separator plate from the front of the machine onto the saddle.

2. Mechanism for feeding fillers to the saddle of a casing-in machine, comprising a supporting bar extending from the front of the machine and terminating adjacent to the saddle, means for raising and lowering the supporting bar, a separator plate extending from the front of the machine and terminating at the saddle, guide rails parallel to and extending each side of the supporting bar, and fingers for pushing and clamping jaws for conveying the fillers along the supporting bar and over the separator plate from the front of the machine onto the saddle.

3. Mechanism for feeding fillers to the saddle of a casing-in machine, comprising a supporting bar extending from the front of the machine and terminating adjacent to the saddle, a separator plate extending from the front of the machine and terminating at the saddle, guide rails parallel to and extending each side of the supporting bar, means for raising the supporting bar and the guide rails, and fingers for pushing and clamping jaws for conveying the fillers along the supporting bar and over the separator plate from the front of the machine onto the saddle.

4. Mechanism for feeding fillers to the saddle of a casing-in machine, comprising a supporting bar extending from the front of the machine and terminating adjacent to the saddle, a separator plate extending from the front of the machine and having its inner end attached to the saddle, guide rails parallel to and extending each side of the supporting bar, and fingers for pushing and clamping jaws

for conveying the fillers along the supporting bar and over the separator plate from the front of the machine onto the saddle.

5. Mechanism for feeding fillers to the saddle of a casing-in machine, comprising a supporting bar extending from the front of the machine and terminating adjacent to the saddle, a separator plate having a beveled and inclined end at the front of the machine and having its inner end attached to the saddle, guide rails parallel to and extending each side of the supporting bar, and fingers for pushing and clamping jaws for conveying the fillers along the supporting bar and over the separator plate from the front of the machine onto the saddle.

6. Mechanism for feeding fillers to the saddle of a casing-in machine, comprising a channel member extending from the front of the machine and terminating adjacent to the saddle, means for raising and lowering the channel member, a filler supporting bar carried by the channel member, guide rails parallel to and extending each side of the supporting bar carried by the channel member, a separator plate extending from the front of the machine and terminating at the saddle, and means conveying the fillers along the supporting bar and over the separator plate from the front of the machine onto the saddle.

7. Mechanism for feeding fillers to the saddle of a casing-in machine, comprising a channel member extending from the front of the machine and terminating adjacent to the saddle, means for raising and lowering the channel member, a filler supporting bar carried by the channel member, guide rails attached to the edges of and extending down into the channel member, a fixed separator plate extending from the front of the machine and terminating at the saddle, and means for conveying the fillers along the supporting bar and over the separator plate from the front of the machine onto the saddle.

8. Mechanism for feeding fillers to the saddle of a casing-in machine, comprising a channel member extending from the front of the machine and terminating adjacent to the saddle, means for raising and lowering the channel member, a filler supporting bar carried by the channel member, guide rails adjustably attached to the sides of the channel member, a fixed separator plate extending from the front of the machine and terminating at the saddle, and means for conveying the fillers along the supporting bar and over the separator plate from the front of the machine onto the saddle.

9. Mechanism for feeding fillers to the saddle of a casing-in machine, comprising a supporting bar extending from the front of the machine and terminating adjacent to the saddle, a separator plate extending from the front of the machine and terminating at the saddle, and reciprocating and oscillatory

fingers for pushing and reciprocatory and oscillatory clamping jaws for conveying the fillers along the supporting bar and over the separator plate from the front of the machine onto the saddle.

10. Mechanism for feeding fillers to the saddle of a casing-in machine, comprising a supporting bar extending from the front of the machine and terminating adjacent to the saddle, a separator plate extending from the front of the machine and terminating at the saddle, means extending each side of the supporting bar for guiding the lower edges of the fillers, and means for conveying the fillers 15 along the supporting bar and over the separator plate from the front of the machine into the saddle.

CARL SCHRAMM.
